FIREARM FORE END

Harold L. Hameister, Keyport, N. J., assignor to
Remington Arms Company, Inc., Bridgeport,
Conn., a corporation of Delaware

Application January 22, 1949, Serial No. 412

Term of patent 14 years

(Cl. D30—1)

To all whom it may concern:

Be it known that I, Harold L. Hameister, a citizen of the United States, residing at Keyport, county of Monmouth, and State of New Jersey, have invented a new, original, and ornamental Design for a Firearm Fore End, of which the following is a specification, reference being had to the accompanying drawing, forming part thereof.

In the drawing:

Fig. 1 is a perspective of a firearm fore end embodying my novel design in place on a firearm, contiguous parts of the firearm being shown in broken lines for illustrative purposes only.

Fig. 2 is a bottom plan view of a fore end embodying my novel design, detached from the firearm.

I claim:

The ornamental design for a firearm fore end, as shown and described.

HAROLD L. HAMEISTER.
